corporation of Delaware

Application October 2, 1931, Serial No. 566,419
Renewed July 27, 1932

8 Claims. (Cl. 123—148)

This invention relates to ignition apparatus for internal combustion engines, and more particularly to the ignition timer and distributor unit.

Heretofore, it has been the practice to provide an ignition timer and distributor unit driven by a shaft which carries the ignition timer cam and the distributor roller and which is so connected with the engine that the said shaft will make one complete revolution during one cycle of operation of the engine. When providing such a unit for a four-cycle internal combustion engine, the shaft of said unit is driven preferably by the valve cam shaft of the engine at a speed ratio of one to one. Since the valve cam shaft of the engine operates at one-half engine speed in a four-cycle internal combustion engine, the shaft of the ignition unit will rotate once during each two revolutions, or during one cycle of operation of the four-cycle internal combustion engine. Similarly, if the ignition unit is to be applied to a two-cycle internal combustion engine, the unit is driven directly by the engine crank shaft. Hence, the shaft of said ignition unit will rotate once during each revolution of the crank shaft of the two cycle engine and hence during each cycle of operation thereof.

In some instances it may be advantageous to drive the shaft of the ignition unit at a speed less than the cycle speed of the engine, for example, less than one-half engine speed where applied to a four-cycle engine, or less than engine speed when applied to a two-cycle engine. It is one of the objects of the present invention to provide an ignition timer and distributor unit operated by a shaft which is driven at one-half cycle speed, for example, one-fourth engine speed where applied to a four-cycle internal combustion engine, or one-half engine speed where applied to a two-cycle engine.

Further objects and advantages of the present invention will be apparent from the following description, reference being had to the accompanying drawing wherein a preferred embodiment of one form of the present invention is clearly shown.

The figure of the drawing is a wiring diagram illustrating a form of the invention.

Referring to the wiring diagram, 20 designates the shaft of the ignition timer and distributor unit, said shaft being driven by the engine (not shown) at a speed corresponding to one-half the cycle speed of the engine, namely, one-fourth engine speed for a four-cycle engine, or one-half engine speed for a two-cycle engine. The shaft 20 drives a cam 21, which cooperates with a cir-

cuit interrupter comprising a pair of contacts 22 and 23, the former being grounded at 24 and the latter being carried by a metal lever 25 which is insulatingly supported by a pivot 26. The lever 25 carries a cam rubbing block 27 cooperating with cam 21. Leaf spring conductor 28 conducts current from the terminal 29 to the lever 25 and operates to urge the contact 23 toward the contact 22 and the rubbing block 27 toward the cam 21.

The terminal 29 is connected with condenser 30 by wire 31 with an ignition coil primary winding 32 which is connected with a switch 33 with a battery 34 grounded at 35. An ignition coil secondary winding 36 is grounded upon the battery through the switch 33 and is connected with the central contact 37 of the ignition distributor. The contact 37 engages the central part of a distributor rotor driven by the shaft 20. The rotor 38 is provided with diametrically opposite segments 39 and 40, each of which is adapted to distribute sparking impulses to either of two distributor posts or terminals 41, 42 connected by wires 43 and 44 respectively, with spark plugs 45 and 46.

The disclosed embodiment of the present invention is constructed and arranged for providing sparking impulses for a two cylinder engine. The timer and distributor unit is constructed so as to rotate in a clockwise direction, as indicated by arrows 47 and 48. Since the shaft 20 rotates at one-half cycle speed during each cycle of operation of the engine, the shaft 20 will turn one-half a revolution. Therefore, the four-lobe cam 21 will cooperate with the circuit interrupter to separate the contacts 22 and 23 twice during one-half revolution of the shaft 20. Each time the contacts 22, 23 are separated one of the segments of the rotor 38 will be adjacent one of the posts of the distributor. For example, at one instant of separation of contacts 22, 23 the segment 40 will be adjacent the distributor post 41 and at the next instant of separation of contacts 22, 23 the segment 40 will be adjacent the distributor post 42. Thus the two sparking

impulses required for the operation of the two-cylinder engine are generated and distributed consequent to the one-half turn of the timer distributor driving shaft 20. During the next cycle of operation of the engine, the shaft 20 completes the other half turn of its rotary movement and during this other half turn the segment 40 is inactive, but the segment 39 is operative to distribute sparking impulses successively to the posts 41 and 42.

It is apparent that the present invention may be applied to the construction of ignition timer and distributor units for engines having any number of cylinders. For example, if the engine 5 has three cylinders, the cam 21 will be provided with six lobes so that three sparking impulses will be created during each half turn of the shaft 20. The distributor will be provided with three distributor posts with which cooperates a segment 10 similar to the segment 38, having diametrically opposite distributing segments 39 and 40. The distributor posts will be arranged sixty degrees apart, instead of ninety degrees, as in the disclosed form for a two-cylinder engine. Likewise, 15 an ignition timer unit embodying the present invention and constructed and arranged for a four-cylinder engine will have eight cam lobes and four distributor posts arranged on one side of the distributor head and spaced forty-five 20 degrees apart.

It is, therefore, apparent that any ignition timer and distributor unit embodying the present invention will require its cam 21 to have twice as many lobes as there are engine cylinders to be 25 fired during each engine cycle; and that the distributor head will be provided with as many distributor posts as there are engine cylinders and that these distributor posts will be located in an arcuate row and spaced apart at an angle 30 equal to one hundred eighty degrees divided by the number of engine cylinders. In each case, the distributor rotor required to cooperate with such distributor heads will be one having two diametrically opposite distributing segments, 35 each segment distributing sparking impulses to all of the distributor posts and then remaining inactive while the opposite segment distributes to all of the distributor posts.

It will be apparent from the foregoing description of the construction and mode of operation of ignition apparatus embodying the present invention, that said invention contemplates a distributor head having a center terminal and 40 N circularly arranged posts equal in number to the explosion periods during an engine cycle. The circularly arranged posts are connected respectively with engine spark gaps. There is a distributor rotor connected with the center terminal and having R (a plurality of) equiangularly 45 spaced branches or arms movable past said posts, said posts and arms being so located and arranged that, during one engine cycle, one arm serves all of the posts and that, during the next succeeding engine cycle, another arm serves all 50 of the posts, and so on until all of the arms have served. The angular spacing of the circularly arranged posts is $360^{\circ} \div R \div N$. The rotor is rotated by the engine at the rate of

$$\frac{1}{R}$$

revolutions during each engine cycle. The induction generating means is controlled by circuit interrupter means comprising B circuit breakers 65 operated by a cam having

$$\frac{N \times R}{B}$$

cam lobes and operated by the engine at the 70 rate of

$$\frac{1}{R}$$

revolutions during an engine cycle, B being so chosen that the quotient will be an integer. The 75 following tabulation shows how the present in-

vention can be applied to engines having different numbers of cylinders, R also varying:

No. of rotor branches R	Explosion periods during each engine cycle N	Ratio of rotor speed to engine cycle speed $\frac{1}{R}$	Angular spacing of spark gap posts $\frac{360^{\circ}}{NR}$	L, number of cam lobes $\frac{NR}{B}$				
				(B=1)	(B=2)	(B=3)	(B=4)	(B=5)

While the form of embodiment of the present invention as herein disclosed, constitutes a preferred form, it is to be understood that other forms might be adopted, all coming within the 110 scope of the claims which follow.

What is claimed is as follows:

1. Ignition apparatus for internal combustion engines comprising, in combination, an ignition timer including a circuit breaker for the primary circuit and a cam for operating the circuit breaker whose lobes number twice the number of engine cylinders, a distributor for the secondary circuit comprising a head carrying distributor posts whose angular spacing equals 180° divided by the 115 number of engine cylinders, and a double end rotor cooperating with said posts, said rotor having diametrically opposite distributing arms, and a shaft driving the cam and rotor and operated by the engine at one-half engine cycle speed. 125

2. Ignition apparatus for internal combustion engines comprising, in combination, an ignition timer including a circuit breaker for the primary circuit and a cam for operating the circuit breaker whose lobes number twice the number of engine 130 cylinders, a distributor for the secondary circuit comprising a head carrying distributor posts, and a double end rotor cooperating with said posts, said rotor having diametrically opposite distributing arms, and a shaft driving the cam and rotor and operated by the engine at one-half engine cycle speed. 135

3. Ignition apparatus for internal combustion engines comprising, in combination, an ignition timer including a circuit breaker for the primary 140 circuit and a cam for operating the circuit breaker said cam having lobes numbering twice the number of engine cylinders, and engine driven shaft driving the cam at one-half engine cycle speed, and a distributor for the secondary circuit 145 including a head carrying distributor posts and a rotor driven by said shaft at timer cam speed.

4. Ignition apparatus for internal combustion engines having N explosion periods during an engine cycle comprising, in combination, a distribu- 150

tor head having a center terminal and N circularly arranged posts connected respectively with engine spark gaps and a distributing rotor connected with the center terminal and having R (a plurality of) branches or arms spaced $360/R$ degrees and movable past said posts, said posts and arms being equiangularly spaced $360/NR$ degrees so that, during one engine cycle, one of the arms serves all of the posts and that, during the next 10 succeeding cycle, another of the arms serves all of the posts, engine driven means for turning the rotor at the rate of

$$\frac{1}{R}$$

revolution during each engine cycle, and means for causing a sparking impulse to be delivered to the center terminal each time a rotor arm is adjacent a post.

5. Ignition apparatus for internal combustion engines having N explosion periods during an engine cycle comprising, in combination, a distributor head having a center terminal and N circularly arranged posts connected respectively with engine spark gaps and a distributing rotor connected with the center terminal and having R (a plurality of) branches or arms spaced $360/R$ degrees and movable past said posts, said posts and arms being equiangularly spaced $360/NR$ degrees so that, during one engine cycle, one of the arms serves all of the posts and that, during the next succeeding cycle, another of the arms serves all of the posts, engine driven means for turning the rotor at the rate of

$$\frac{1}{R}$$

revolution during each engine cycle, induction generating means connected with the center terminal and a circuit interrupting means comprising B circuit breakers operated by a cam having

$$\frac{N \times R}{B}$$

cam lobes and operated by the engine at the rate of

$$\frac{1}{R}$$

revolution during each engine cycle, B being a number such that the quotient

$$\frac{N \times R}{B}$$

will be an integer.

6. Ignition apparatus for internal combustion engines having 2 explosion periods during an engine cycle comprising, in combination, a distribu-

tor head having a center terminal and 2 circularly arranged posts connected respectively with engine spark gaps and a rotor connected with the center terminal and having 2 rotor branches or arms, said posts and arms being so located and arranged that, during one engine cycle, one arm serves both posts and that, during the next succeeding cycle, the other arm serves both posts, engine driven means for turning the rotor at the rate of $\frac{1}{2}$ revolution during each engine cycle and means for causing a sparking impulse to be delivered to the center terminal each time a rotor arm is adjacent a post.

7. Ignition apparatus for internal combustion engines having 2 explosion periods during an engine cycle comprising, in combination, a distributor head having a center terminal and 2 circularly arranged posts connected respectively with engine spark gaps and a rotor connected with the center terminal and having 2 rotor branches or arms, said posts and arms being so located and arranged that, during one engine cycle, one arm serves both posts and that, during the next succeeding cycle, the other arm serves both posts, engine driven means for turning the rotor at the rate of $\frac{1}{2}$ revolution during each engine cycle, induction generating means connected with the center terminal and a circuit interrupting means comprising B circuit breakers operated by a cam having

$$\frac{4}{B}$$

cam lobes and operated by the engine at the rate of $\frac{1}{2}$ revolution during each engine cycle, B being equal to 1, 2 or 4.

8. Ignition apparatus for internal combustion engines having N explosion periods during an engine cycle comprising, in combination, a distributor head having a center terminal and N circularly arranged posts connected respectively with engine spark gaps and a rotor connected with the center terminal and having R distributing branches or arms movable past said posts, said posts and arms being so located and arranged as to operate alternately to serve all of the posts, means driven by the engine for turning the rotor at the rate of

$$\frac{1}{R}$$

revolution during each engine cycle, and means for causing a sparking impulse to be delivered to the center terminal each time a rotor arm is adjacent a post.
